UNITED STATES PATENT OFFICE.

GEORGE W. SAATHOFF, OF SOUTH ORANGE, NEW JERSEY, ASSIGNOR TO DOHERTY RESEARCH COMPANY, OF NEW YORK, N. Y., A CORPORATION OF DELAWARE.

SURFACE CONDENSER.

Application filed December 13, 1922. Serial No. 606,560.

This invention relates to a surface condenser, and, more particularly, to apparatus for preventing the leakage of cooling fluid from the cooling fluid compartments through the joints of the condenser apparatus into the condensate or pure liquid compartment.

In condensers of the type in which the cooling water flows through cooling tubes extending through a vapor space between partitions separating the vapor space from the end water compartments, it is difficult, if not impossible, to maintain the joints between the ends of the tubes and the partitions absolutely fluid tight. As a result, there is a tendency for a portion of the cooling liquid to leak from the cooling fluid chambers through the joints to the vapor chamber and thus become mixed with the condensate formed in the vapor chamber. As condensers of this type are usually employed when the cooling fluid is not of sufficient purity or softness for use in boilers or other apparatus to which the condensate is returned, or for drinking purposes, the leakage of the cooling fluid into the vapor chamber tends to cause the continued contamination of the condensate and the accumulation of saline products or impurities in the boilers or other apparatus to which the condensate is applied and thus interferes with the operation of the apparatus.

An object of the present invention is to provide apparatus for condensing vapors in which the leakage of cooling fluid into the vapor system is positively prevented.

A further object of the invention is to provide apparatus for condensing vapors under reduced pressure in which the tendency for cooling fluid to leak into the vapors is opposed by a fluid under pressure interposed between the cooling fluid compartment and the vapors.

Further objects and features of the invention are to provide a surface condenser in which a pressure chamber is interposed between the partition separating the vapor compartment from the cooling compartment; to provide an improved packing about the tubes passing through said pressure chamber; and to provide a simple and effective construction for said pressure chamber.

These and other objects and features are described and set forth in the accompany-

ing specification and claims and illustrated in the accompanying drawings, in which:

Fig. 1 is a vertical sectional elevation of a condenser embodying a preferred form of the invention, and,

Fig. 2 is a detail sectional view of a portion of the condenser showing a manner of packing the joints about the cooling tubes.

In the present invention the leakage of cooling water into the vapor space is opposed and prevented by forcing a distilled water or a water which is sufficiently pure, so as not to contaminate the condensate, as, for example, a portion of the condensate itself against the joints through which leakage may occur, in a direction opposed to that of said leakage. This is preferably accomplished by interposing an intermediate, pressure fluid chamber between the partition through which leakage may take place and the vapor space, and filling this intermediate chamber with condensate from the vapor chamber under sufficient pressure to prevent the leakage of cooling fluid through the joints in the partition. The intermediate chamber is preferably formed by a partition slightly spaced from the vapor side of the end partitions and through which the cooling tubes extend. The pressure of the liquid in this intermediate chamber is maintained somewhat above that of the fluid in the cooling liquid compartment, in order to positively insure against the leakage of any cooling fluid into the vapor compartment. If a small portion of the fluid leaks from the intermediate, pressure chamber into the cooling fluid compartment, it will be mixed with the cooling water and if a portion leaks into the vapor compartment it will commingle with the condensate. The quantity of liquid thus lost from the pressure chamber is replaced by fresh condensate or other pure liquid and the quantity thus lost is reduced to a minimum by suitable packings about the tubes in the partitions.

Referring to the accompanying drawings, the invention is illustrated as embodied in a type of condenser in which cooling water is supplied through an inlet 10 to the lower portion of a supply and distributing chamber 12 from which it is distributed among a number of tubes 14 extending from a partition 16 forming one wall of the chamber 12 through a vapor compartment 18. The

2
liquid flowing through the tubes 14 is discharged into a chamber 20 separated from the other side of the vapor space 18 by a partition 22 in which the ends of the tubes 5 are mounted. From the upper portion of the chamber 20 the liquid is withdrawn through an outlet pipe 24. The vapor compartment 18 is formed by a cylindrical shell 26 having an inlet 28 in its upper wall 26 having an inlet 28 in its upper wall 10 through which the vapor is admitted to the compartment. The condensate formed in the vapor compartment flows into a well 30 in the bottom wall of the compartment and is withdrawn through a drawoff pipe 32 by 15 means of a pump 33 and forced through a delivery line 34.

As the vapor compartment is normally maintained under reduced pressure and the liquid is supplied to the cooling liquid compartments at atmospheric or above atmospheric pressure, there is a tendency for liquid to leak from the chambers 12 and 20 about the ends of the tubes 14 into the vapor compartment 18 and thus contaminate the 20 condensate formed in the vapor compartment. To prevent this leakage a portion of the condensate is diverted from the delivery pipe 34 through a branch pipe 36 and pressure regulating valve 38 and supplied through branch pipes 40 and 42 to intermediate or pressure chambers 44 and 46 formed between the partitions 16 and 22 respectively and the vapor chamber 18 by means of partitions 48 and 50 spaced a short 25 distance from the partitions 16 and 22 respectively. The tubes 14 extend through aligned openings 52 and 54 in the partitions 16 and 22, and 48 and 50, the joints about the tubes being rendered as tight as practicable by means of suitable packing or other means.

To insure against any seepage or leakage of fluid through the partitions into the condensate, the pressure of the liquid supplied 45 to the chambers 44 and 46 is maintained slightly above that of the chambers 12 and 20. The pressure in chambers 44 and 46 is maintained substantially constant by the regulating valve 38 so as to be slightly 50 higher than the pressure in chambers 12 and 20, regardless of the variations in pressure in the line 34. A slight leakage of the condensate liquid into the cooling liquid may take place but by a suitable regulation of 55 the relative pressures on opposite sides of the partitions, this leakage may be made small. Some of the condensate liquid may also leak from the chambers 44 and 46 into the compartment 18 but this liquid being 60 substantially the same as that in the compartment 18 does not contaminate the condensate drawn from the well 30.

To enable the tubes to be easily mounted in all of the partitions and to form sufficiently tight joints to minimize the leakage 65

of liquids, each of the joints is preferably provided with a suitable packing device. To this end the openings 52 in the partitions 48 and 50 are countersunk and threaded as at 56 and a packing ring 58 is placed 70 in the recess formed between the enlarged portion and the outer surface of the tube 14. This packing ring is then compressed by means of a threaded ring or spanner nut 60 in the enlargement 56, thereby forming a 75 tight joint about the tube.

The openings 54 in the partitions 16 and 22 are larger than the outer circumference of the tubes 14 to permit the insertion of a wrench for operating the nut 60. Each opening 54 is provided with an inwardly projecting flange 62 and a flanged ring 64 is positioned in the opening to rest against the flange 62 and close the opening around the tube. A packing ring 66 is placed in the opening 54 and is compressed between the ring 64 and a spanner nut 68 threaded into the larger portion of the opening 54. In this manner the loss of condensate liquid through leakage may be reduced to a minimum 80 without the necessity for a very exact fitting of the tubes in the openings and exact alignment of the openings.

The partitions 48 and 50 may be held in spaced relation to the partitions 16 and 22 95 in any suitable manner. Preferably they are held in position and a tight chamber formed by interposing rings 70 and 72 between the partitions 16 and 48 and 22 and 50 respectively, and bolting or otherwise fastening these rings with the partitions between suitable flanges projecting outwardly from the shell 26 and the walls of the chambers 12 and 20. A very simple construction is thus provided and one which permits the 100 apparatus to be readily taken apart when necessary. This construction also permits existing condensers to be readily adapted to utilize the present invention with a small 110 change in construction.

Through the above invention the leakage of cooling fluid into the condensate chamber or compartment may be positively prevented without interfering with the degree 115 of vacuum maintained in the vapor chamber. The invention also requires but very little additional apparatus or changes in construction over the ordinary type of condenser and but very little attention in operation.

Having described the invention, what I claim and desire to secure by Letters Patent is:

1. A condenser apparatus which comprises, a vapor compartment, cooling fluid compartments at opposite ends of said vapor compartment, cooling tubes extending through said vapor compartment from one cooling fluid compartment to the other, an intermediate chamber between each cooling 125

fluid compartment and the vapor compartment, and means for withdrawing condensate from said vapor compartment and forcing a portion of said condensate to said intermediate chambers at a definite regulated pressure.

2. A condenser apparatus which comprises, a vapor compartment, a cooling fluid compartment at one end of said vapor compartment, cooling tubes extending from said cooling fluid compartment into and closed to

said vapor compartment, an intermediate chamber between said vapor compartment and said cooling fluid compartment, a pump for withdrawing condensate from said vapor compartment, a branch pipe from the discharge from said pump to said intermediate chamber and a pressure regulating valve in said branch pipe. ¹⁵

In testimony whereof I affix my signature.

GEORGE W. SAATHOFF.
